OVERHEAD DOOR HOLDER

Michael J. Sasgen, Chicago, Ill., assignor to
Grand Specialties Company, Chicago, Ill., a
corporation of Illinois

Application March 22, 1933, Serial No. 662,099

3 Claims. (Cl. 292—263)

This invention relates to improvements in devices for controlling the opening and closing of a horizontally swinging door, and has special relation to a device to be arranged at the top 5 of the door, for limiting the opening of the door; for yieldingly and definitely retaining the door at the limit of its opening movement; for definitely causing the folding of the parts of the device in a desired and predetermined manner or direction; and, in a preferred form for frictionally retaining the door in its position when opened to any degree.

Another feature resides in an adjustable member which can be readily changed from a position 15 wherein it will cause the positive retaining of the door at the outer limit of its movement, to another position which will cause the mechanism to act merely as a limit stop but not a door holder.

20 A valuable feature relates to the simple and direct acting means which I employ to permit the door to be swung inwards from its outer limit even when the adjustable member is set to hold the door open. The device includes two 25 cooperating levers held pivoted together by a pivot bolt, and means for relieving the pivot bolt of all except longitudinal strains thus reducing the wear on this vital part.

30 A further feature relates to an arrangement whereby the device can as easily be installed for use on a left-hand as on a right-hand door. In other words, the levers can be arranged to be installed to fold together in either direction in accordance with the manner in which the door 35 is hung, by merely swinging the levers around in relation to each other before they are installed.

The invention consists in the means hereinafter 40 fully disclosed and particularly pointed out in the appended claims, the accompanying drawings, forming part of the specification, and the following description setting forth in detail one embodiment exemplifying the invention, such disclosed arrangements of parts and devices and combinations of parts constituting, however, but one of various applications of the principle of the invention.

In said drawings:—

Figure 1 is a top plan view showing the device 50 installed in position for use and shown open in full lines and closed in dotted lines;

Fig. 2 is an enlarged fragmentary longitudinal vertical section on the line 2—2 of Fig. 1;

55 Figs. 3 and 4 are fragmentary horizontal sections on the line 3—3 and the line 4—4 respectively of Fig. 2;

Fig. 5 is a view similar to Fig. 3 but showing the two arms in closed position;

60 Figs. 6, 7 and 8 are vertical sections on the lines 6—6, 7—7 and 8—8 respectively of Fig. 2;

Fig. 9 is a fragmentary longitudinal, vertical section on the line 9—9 of Fig. 1;

Fig. 10 is a sectional view similar to Fig. 3 but showing the device arranged to close the arms in the opposite direction;

Fig. 11 is a view similar to Fig. 2 but showing a lifting cam instead of a friction abutment;

Fig. 12 is a view similar to Fig. 3 but showing the lifting cam;

Fig. 13 is a vertical section on the line 13—13 10 of Fig. 11;

Fig. 14 is a view similar to Fig. 4 but showing the lifting cam instead of the friction abutment;

Fig. 15 is a view similar to Fig. 5 but showing the lifting cam;

Fig. 16 is a view similar to Fig. 10 but showing the lifting cam.

In said drawings 1 represents a door mounted on the door frame 2 by hinges 2' to swing around horizontally. In Fig. 1 one of my improved door 20 holders 3 is shown as having one end secured to the door near its top and the other end secured to the top member of the door frame, and is shown in extended condition in full lines holding the door swung open, and in dotted lines in 25 folded condition and the door closed.

The device comprises two members or arms 4 and 5 which are arranged to swing around horizontally and are pivotally connected together at one end by a vertical pivot bolt 6. The opposite ends of the levers are pivotally connected respectively to the door by a pivot 7 and to the door frame by a pivot 8, the ends being provided with bracket or attachment members 9 and 10 30 respectively for providing the pivotal mountings. In each case the bracket is U-shaped and the cooperating end 11 of the lever is received between the jaws of the bracket, the pivot bolt 8 passing through the two jaws of the bracket and the 35 end of the lever.

The lever end rests upon a ring of balls 12 which are mounted in a groove provided in the underside of the lever end. As each end of the device is thus mounted it will be seen that the lever actually floats on balls and thus can be 40 swung quite easily so far as the end mountings are concerned. Furthermore, practically no oiling of these ends is necessary, and they are very durable in use.

At the connected ends of the levers and surrounding the pivot bolt 6 the levers are both enlarged horizontally providing two circular palms or enlargements 13 and 14. The enlargement 13 has a circumferential upstanding rim 15 providing a hollow space to receive certain parts to be 50 described, and the cooperating end 14 is in the form of a cover to close said hollow space. The pivot bolt 6 is centrally located and passes through both of these enlargements and holds them pressed together. The top of the rim 15 55

60

is formed to provide a circumferential shoulder 16 and the cover is formed to fit within this circumferential shoulder. This construction provides an enlarged bearing which is ample to take the pull and push of operation and to relieve the pivot bolt 6 of any strains except those incident to holding the two parts together. The top edge 17 of the rim 15 bears directly against the under side of the cover 14 and this construction which provides the side bearing and the top bearing not only relieves the pivot bolt of all side strains but retains the two levers securely in parallel planes.

There are several functions of the device which it is desired to provide for.

The simplest of these is merely to prevent the door from being swung open too far and to make certain that when the door starts to close the levers will begin to collapse from their straight-line extended position in the right direction.

Other functions relate to causing the device to serve as a yielding lock to retain the door in full open position, to serve as a friction-holding device to yieldingly hold the door in any part-way open position and to serve as a door-holding device without that of retaining it in a part-way open position.

In Figs. 2 to 8 inclusive I have shown the form which includes the friction means. Within the hollow space in the palm 13 there is secured a circular or ring-like member 18 which is secured to the underside of the cover member 14 by rivets 19. This ring member has an outer diameter nearly as large as the space within the rim 15 and is provided at one side in its outer surface with a notch 20 having slightly-inclined ends 21 for a purpose to be described, and at its inner side directly opposite to the notch 20 with an inwardly extending tongue or projection 22. Both the notch and the projection are on the side of the cover opposite to its arm 5.

The other lever 4 is provided with a yielding projection 23 arranged to move radially in relation to the ring member 18 which acts as an abutment for the movable member 23. The member 23, as best shown in Fig. 2, comprises a central stop member 24 mounted within a tubular member 25 which in turn is mounted in a longitudinal guide opening 26 provided in the arm 4 adjacent to its inner end and radially to the ring 18.

The stop member 24 may be provided on its inner end with one or more V-shaped or narrow edges 27 for contact with the outer surface of the ring 18 and is adapted, at times, to be forced against the ring with considerable pressure thus providing friction enough to hold the door yieldingly in any part-way open position.

The member 24 which may be termed a locking bolt is cylindrical in shape and at its inner end is flattened at its top and bottom, as best shown at 28 in Fig. 8; and the inner end of the hole in which the member 24 slides is of a similar flattened shape top and bottom to hold the member 24 against turning around and with its V-shaped edges at its inner end properly positioned against the outer cylindrical surface of the ring 18, that is in longitudinal relation thereto.

The inward movement of the member 24 is limited by shoulders 29 at the rear ends of the flats 28 and the inner ends of the similarly-shaped opening in the tubular member 25. The member 24 is yieldingly urged toward the inner limit of its movement by a spring 30 arranged within the tubular member 25 and abutting at its rear end

against a screw plug 31 mounted in the rear end of the tubular member 25. By adjusting the screw plug in or out the tension of the spring 30 can be adjusted to obtain the results desired.

The results desired are of course the retaining of the door in open position with the least resistance, under the circumstances, which it is necessary to apply.

Many details affect the necessary adjustment of the spring 30 depending of course upon the particular circumstances, size, weight and position of the door and whether an inside or an outside door. The easy adjustment of the spring 30 from the outside by a screw-driver makes it very easy to adjust the holder to the particular door upon which it is used and after it is in place, and also to change the action of the stop from an easy holding action to a stronger holding action if such is required to properly hold the door against drafts, or the like. If the holding action is too weak it can easily be made stronger by simply screwing in the plug 31 and thus increasing the tension of the spring 30. This adjustment of the spring 30 in no way affects the tension of the spring 34 which does not require adjustment as its function is merely to hold the guide plug 25 rearwardly against the shoulder against the manually operated cam member 36. The tubular member is mounted to slide back and forth, that is radially of the pivot bolt 6 and for the purpose of holding the member 24 from rotating it is prevented from rotating.

In the form shown this is accomplished by making its outer surface hexagonal in shape as best shown in Fig. 7, and the hole in which it slides is of like shape. The member 25 is provided on its outer surface with an annular shoulder 32 near its outer end and the hole in which it slides is provided with a cooperating shoulder 33 near its forward end and between these two shoulders is arranged a coiled spring 34 which serves to urge the member 25 rearwardly. If the member 25 is free to move rearwardly the inner end of the member 24 is withdrawn from contact with the ring abutment 18 and does not function to control the movements of the door. For preventing the escape of the member 24 and for forcing it inwardly against the action of the spring 34, I provide an adjustable stop at its rear end having two positions: one for allowing it to be pushed back free of the ring 18, and the other where it is held against the periphery of the ring 18 and ready to be pushed into the holding notch 20 whenever the door is opened far enough.

The adjustable stop consists of a bolt-like member 35 arranged vertically and having a T-shaped head 36 at its upper end arranged directly in line with the member 25. The member 35 is held in position with the T-head down against the upper side of the arm 4, as best shown in Fig. 2, by a handle member 37 and a coiled spring 38 on the shank of the member 35 and between the arm 4 and the handle member 37. The spring 38 adds friction so that the member 35 will stay in the position as set. When it is set with its T-head extending lengthwise of the arm 4 the tubular member 25 is held against being forced back by the spring 34 and hence the inner end of the member 24 is yieldingly held pressed against the periphery of the ring member 18. When the member 35 is turned so that its T-head extends across the arm 4 the tubular member is pushed back by the spring 34 into contact with the side of the T-head and the member 24 is withdrawn from contact with the ring 18. Preferably the han-

dle 37 is elongated and extends in line with the T-head 36 so that it will indicate the position of the T-head, whether in door-locking or door-unlocked position.

- 5 When the T-head 36 is turned to hold the tubular member 25 inwardly and the door is opened to its widest extent the projection 24 is forced into the notch 20, as best shown in Fig. 3. As both the inner end of the member 24 and the 10 ends 21 of the notch 20 are inclined they tend to force the bolt member 24 out of the notch, if the door is swung with sufficient force, against the resiliency of the spring 38. That is, when the door has been opened so that the arms 4 and 5 are 15 in substantially straight-line extended position, the door can be swung shut by a forceful pull on the door knob in the usual way, the force applied being sufficient to force the bolt 24 out of the notch 20.
- 20 To assure the folding of the arms 4 and 5 back in the direction from which they were extended, there is provided a yielding stop which tends to throw the arms 4 and 5 out of substantially straight alinement in the right direction.

25 This yielding stop means consists of the rigid projection or tooth 22 on the ring 18 and a yielding member carried by the opposite arm. This member consists of a U-shaped spring 39 which is received in an open-sided pocket 40 formed around the pivot bolt 6 on the arm 4. Preferably the spring 39 is formed with an eye 41 at its base through which the pivot bolt 6 passes and which arrangement keeps the spring in position; the outer ends 42-43 project out into the path of the 30 projection 22 and as the arms are swung to their extended position, as best shown in Fig. 3, the projection 22 tends to close the spring, the spring being held against bodily movement by the walls of the pocket 40. When the door is unlocked and 35 allowed to close, the spring 39 starts the arms to swing in the direction opposite to that in which they swung when opening. It will be readily seen from Fig. 3 that the same action would occur if the arms were opened by swinging in the opposite direction. In other words, without alteration the device can be properly applied to either a right- or a left-hand swinging door. The 40 notch 20 in the ring 18 is wider than the inner end of the stop and the yielding holding means serves to retain the two arms slightly out of straight line 45 position when the door is swung fully open, as plainly indicated in Figs. 3 and 4.

50 In some instances it is not desirable to provide any means for holding the door, frictionally, in a partly-open position. In such case the device is the same in every particular except that the abutment ring 18 is replaced by a cam member 44 as shown in Figs. 12 to 16 inclusive. This cam member 44 is secured to the upper cover member 14 55 in any suitable manner as by rivets 45, and is so arranged that when the door is opened and the arms 4 and 5 swung toward straight-line extended position, the member 24 will be pushed back by one of the inclined ends 46 of the cam 44 ready to drop 60 into a central notch 47 in the outer edge of the cam and which is similar to the notch already described. The notch has inclined ends and the bolt member 24, which in this form may have a single rather than a double end, has inclined sides, 65 so that a pull on the door strong enough will force the lock member back and the door can then be swung freely to close it.

70 In this form as in the other, the manually-oper-

able member 35 is provided to set the member 24 either inwardly to locking position or allow it to be forced back out of locking position. Furthermore, in this form as in the other form, the device by reason of the U-shaped spring 39, and the cam 44 being double-ended and symmetrical, the device is capable of being applied with equal facility to either a left- or a right-hand door.

75 I am aware that somewhat similar devices have been produced, but so far as I am aware none has heretofore been produced in which the strains of operation did not tend to distend and prematurely wear out the parts, particularly the central locking parts. By means of the radially-acting locking bolt and the ample bearing between the enlarged palms at the connected ends of the arms 4 and 5, I have avoided these objectionable features and provided a simple device for the purpose which is very durable and which can be arranged to accomplish the features desired.

80 As many modifications of the invention will readily suggest themselves to one skilled in the art, I do not limit or confine the invention to the specific details of construction and operation herein shown and described.

I claim:

85 1. In a device of the kind described, two levers pivotally connected at one end to swing in parallel planes, the connected ends of the levers being enlarged, one of the levers provided with an open-sided centrally arranged pocket on its enlargement, a spring seated in said pocket and having ends projecting from the open side thereof, the other lever provided with a rigid inwardly projecting stop arranged and adapted to engage either one or the other end of said spring depending on the direction in which the levers are swung, the sides of the opening in the pocket constituting 90 spring stops.

2. In a device of the kind described, a pair of 95 levers pivotally connected at one end to swing in parallel planes, a notched abutment on the pivoted end of one lever, a cooperating stop carried on the pivoted end of the other lever, a movable guide plug in which the stop is mounted for limited movement back and forth, means yieldingly holding the guide plug at the rear limit of its movement, independent means for yieldingly holding the stop at the forward limit of its movement, means for readily adjusting the tension of said 100 independent means without changing the tension of the means for yieldingly holding the guide plug.

3. In a device of the kind described and having 105 two swinging levers pivoted together at one end to swing in parallel planes, one of the levers having a centrally arranged notched abutment on its pivoted end, a yielding stop member on the other lever adapted to engage the abutment to yieldingly retain the levers in substantially extended 110 relation, a movable guide member arranged for limited movement back and forth, and in which the stop member is mounted, a spring for yieldingly retaining the guide member at the rear limit of its movement, a second spring for yieldingly retaining the stop member at the forward limit of its movement, means for readily adjusting the tension of the said second spring to meet the requirements, and a manually operable cam member for forcing the guide member inwardly as 115 120 and for the purpose specified.
